W. T. Russell

ATTORNEY

UNITED STATES PATENT OFFICE.

JOHN J. LOCHMAN, OF NEW YORK, N. Y.

RAZOR-BLADE HOLDER.

1,367,611.

Specification of Letters Patent.

Patented Feb. 8, 1921.

Application filed May 8, 1919. Serial No. 295,567.

To all whom it may concern:

Be it known that I, JOHN J. LOCHMAN, a citizen of the United States, and a resident of New York, in the county of New York 5 and State of New York, have invented a certain new and useful Improvement in Razor-Blade Holders, of which the following is a full, clear, and exact specification.

This invention relates more particularly 10 to a class of devices adapted to be used in conjunction with safety razor blades.

My invention has for its object primarily 15 to provide a holder adapted to be employed for removably carrying a safety razor blade whereby the blade may be readily and effect- 20 tually honed or sharpened, and which is of a form to allow blades of various makes to be accommodated therein as well as being of a form to permit the handles of different types of safety razors to be used in conjunction with the holder. The invention re- 25 sides mainly in providing a surface element or plate having a recess or aperture as well as having in spaced proximity to the recess a number of spaced lugs or knobs so that forms of safety razor blades made with ori- 30 fices and those made with marginal beads or flanges may be interchangeably mounted on the element. On the surface element is a bar or jaw having one of its ends pivoted to the element so that it may be swung back and forth crosswise with relation to the recess and the lugs of the surface element for 35 engaging and disengaging the razor blade when applied on the element so that the blade will be removably clamped on the element.

Other objects of the invention are to pro- 40 vide a catch for releasably locking the sec- ond end of the bar and the surface element together; to provide on the surface element a head to allow the handles of different types of razor blades to be removably attached to the element; and to provide a razor blade 45 holder of a simple, efficient and durable construction which may be made in any desired size and shape.

With these and other objects in view the 50 invention will be hereinafter more particularly described with reference to the accompanying drawing forming a part of this specification in which similar characters of reference indicate corresponding parts in all the views, and will then be pointed out 55 in the claims at the end of the description.

In the drawing, Figure 1 is a top plan

of one form of razor blade holder embodying my invention, and which shows one form of razor blade handle attached thereto.

Fig. 2 is a view, partly in detail and 60 partly in section, taken on the line 2—2 of Fig. 1.

Fig. 3 is a sectional view taken on the line 3—3 of Fig. 2.

Fig. 4 is a fragmentary view, partly 65 broken away, showing another form of razor blade handle attached to the head of the holder, and

Fig. 5 shows a plan view of two forms of safety razor blades which may be applied 70 to the holder.

The device or holder has an elongated surface element or plate 10 which may be of any desired shape and size, though the plate is preferably substantially rectangular, and 75 protruding from one end of the plate may be a shank or lug 11 of somewhat narrower width than the plate. In the central part of one face of the plate 10, and adjacent to one of its side edges is a recess 12, though 80 instead of the recess the plate may be apertured. The recess 12 is substantially rectangular, and this recess is of a size to freely accommodate therein the marginal bead or flange, as 13, of a well known form 85 of safety razor blade, as 14 Fig. 5. The recess is of a width approximately one-half the width of the plate or support 10, and protruding from the recessed face of the plate between its second side edge and the 90 recess are a number of spaced knobs or lugs, as 15 and 16. These knobs are preferably circular in shape as well as being spaced from each other, besides being of sizes so as to be freely passed through the holes 17 and 95 18 of another well known make of safety razor blade, as 19 Fig. 5, and the plate 10 is considerably narrower than the razor blade.

In order to removably hold the razor blade 100 from accidental movement when applied on the surface element or plate 10, a bar or jaw, as 20, is provided. This bar may be of a length about the combined length of the plate 10 and its shank 11, and the bar is 105 considerably narrower than the width of the plate. One end of the bar is pivoted, at 21, to the shank of the plate 10 to allow the bar to be swung back and forth crosswise of the plate as well as across the recess 12 so that 110 one edge of the bar will contact with the knobs 15 and 16 of the plate 10.

When the form of razor blade 14 is applied to the device for honing and sharpening, the blade is arranged on the plate so that its flange 13 is disposed in the recess 12 of the plate following the swinging of the bar 20 from the plate, the razor blade being also arranged so that its blade part proper will lay upon the knobs 15 and 16 of the plate, while the cutting edge of the blade 10 protrudes beyond the plate. When the form of razor blade 19 is applied to the device for honing the blade is arranged on the plate 10 so that its knobs 15 and 16 will be disposed through the holes 17 and 18 of the 15 razor blade, and subsequent to this manner of applying either of the blades on the plate the bar 20 is reversely swung upon the plate 10 and upon the razor blade.

Serving as means to releasably lock the 20 bar 20 to the plate 10 whereby the razor blade will be removably clamped against accidental displacement, I provide a catch, as 22. The catch 22 may be of any suitable type, though the form illustrated consists of 25 providing in the central part of the end of the plate 10 which is opposite to the shank 11 a notch, as 23, and on the end of the bar 20 opposite to its pivot 21 is a lug or short finger, as 24, which is disposed angularly 30 from the plate for being adapted to be removably sprung into the notch 23 when the bar is swung upon the plate and upon the razor blade.

To permit handles of various makes of 35 safety razors to be interchangeably used in conjunction with the holder, on the shank 11 is provided a head, as 25. This head may be of any suitable shape, though the head is preferably cylindrical with a rectilinear free 40 end having a threaded socket 26 therein. When the form of handle, as 27 Figs. 1 and 2, is applied to the holder, such a handle is made with a threaded pin 28 protruding from one of its ends, and this threaded pin 45 is removably screwed in the threaded socket 26 of the holder. When a form of handle, as 29 Fig. 4, is applied to the holder, this handle is made with a threaded socket, as 30, in one of its ends. To removably attach the 50 handle 29 to the holder, I provide a nut or union, as 31. This union has a circular disk 32 on both faces of which are threaded pins 33 and 34 which protrude in opposite directions from the central parts of the faces of 55 the disk. One of the pins is screwed in the socket 26 of the head 25 of the holder, and the socketed end of the handle 29 is screwed on the other pin of the union. Thus a 60 holder of a simple and efficient construction is provided whereby different types of safety razor blade handles may be interchangeably used therewith and which also may be used for removably carrying various forms of safety razor blades whereby the blades may

be readily honed and sharpened in the usual 65 fashion.

In the foregoing description, I have embodied the preferred form of my invention, but I do not wish to be understood as limiting myself thereto, as I am aware that modifications may be made therein without departing from the principle or sacrificing any of the advantages of this invention, therefore, I reserve to myself the right to make such changes as fairly fall within the scope 75 thereof.

Having thus described my invention, I claim as new and desire to secure by Letters Patent:—

1. The combination, in a razor blade 80 holder, of a substantially rectangular plate having a recess in one of its faces with spaced knobs protruding from the plate adjacent to the recess, a bar having one end pivoted to one end of the surface element so 85 that its other part may be swung crosswise of the plate as well as crosswise of the recess toward and from the knobs, and a head on the plate, having a threaded socket to allow different handles of safety razors to be 90 removably attached to the plate.

2. The combination, in a razor blade 95 holder, of a substantially rectangular plate having a recess in one of its faces with spaced knobs also protruding from the plate adjacent to the recess, a bar having one end pivoted to one end of the plate so that its 100 other part may be swung crosswise of the plate as well as crosswise of the recess toward and from the knobs, means associated with the bar and with the plate whereby the bar and plate may be releasably locked together, and a head on the plate having a threaded socket to allow different handles of 105 safety razors to be removably attached to the element.

3. The combination, in a razor blade 110 holder, of an elongated plate having a recess in one of its faces with spaced knobs also protruding from the plate adjacent to the 115 recess, a bar having one end pivoted to one end of the plate so that its other part may be swung crosswise of the plate as well as crosswise of the recess toward and from the knobs, means associated with the bar and with the plate whereby the bar and element may be releasably locked together, a head on the plate having a threaded socket, and means removably mounted in the socket whereby a safety razor handle having a 120 threaded socket may be detachably fastened to the head.

This specification signed and witnessed this 7th day of May, A. D. 1919.

JOHN J. LOCHMAN.
